(57) CLAIM

I claim the ornamental design for an infant teether, as shown and described.

DESCRIPTION

FIG. 1 is a perspective view of a teether, according to my new design;

FIG. 2 is a top plan view thereof;

FIG. 3 is a bottom plan view thereof;

FIG. 4 is a front elevation view thereof;

FIG. 5 is a back elevation view thereof;

FIG. 6 is a left side elevation view thereof; and,

FIG. 7 is a right side elevation view thereof.
